United States Patent Office

Des. 193,259
Patented July 17, 1962

193,259

COMBINATION TOASTER AND OVEN OR SIMILAR ARTICLE

Paul O. Rawson, Jr., Trumbull, Conn., and Roger L. Funk, Liverpool, N.Y., assignors to General Electric Company, a corporation of New York

Filed June 29, 1961, Ser. No. 65,852

Term of patent 14 years

(Cl. D81—10)

Fig. 2.

Des. 193,259

PAGE 3

Fig. 3.

Fig. 4.

FIG. 1 is a perspective view of a combination toaster and oven or similar article embodying our design;

FIG. 2 is a front elevation view thereof;

FIG. 3 is a top plan view thereof;

FIG. 4 is a side elevation view thereof.

The rear of the combination toaster and oven or similar article shown in the drawings is substantially plain.

We claim:

The ornamental design for a combination toaster and oven or similar article, substantially as shown and described.
